UNITED STATES PATENT OFFICE

CHARLES J. RAMSBURG, OF EDGEWORTH, PENNSYLVANIA, ASSIGNOR TO THE KOPPERS COMPANY, A CORPORATION OF PENNSYLVANIA

PROCESS OF RECOVERING LIGHT OILS, MOTOR FUEL, AND THE LIKE

No Drawing.

Application filed December 24, 1926. Serial No. 156,986.

My invention relates to a process for recovering light oils, such as benzol and its homologues, toluol, xylol, and other products from fuel gas, such as coke oven gas, coal gas and the like.

My invention further relates to process of treating a petroleum derivative, whereby a useful and advantageous product may be obtained.

10 An object of my invention is to provide a process of recovering light oils from fuel gas in an advantageous form, with heightened efficiency of removal, and without the necessity of recirculation and elaborate heat ex-
15 change.

A second object of my invention is to provide a process of so treating a petroleum derivative that upon subsequently cracking said derivative, the light distillates therefrom will be of advantageous character with respect to their use as motor fuel.

20 A further object of my invention is to provide a process of treating a petroleum derivative containing light aromatic oils, for the recovery of motor fuel, wherein conversion of such oils into undesirable products is avoided.

25 A still further object of my invention is to provide a process for removing gum-forming or other objectionable constituents from distillates of the character indicated, without unnecessary losses.

My invention has for further objects such other new and useful operative advantages or results as may hereinafter be found to obtain.

30 Present practice, with regard to the recovery of light oils from fuel gas, is to circulate over the gas a solvent derived from petroleum, such as gas oil or the like, for the absorption of aromatic hydrocarbon oils from the gas, and subsequently to subject the thereby enriched oil to steam distillation to strip it of said absorbed oils, prior to recirculation over the gas. This stripping process involves extensive apparatus for effecting heat exchange, steam distillation, cooling, and recirculation. Further apparatus, including stills, condensers, agitators, etc., and corresponding manipulations, are required for converting the crude light oil into pure products, such as benzol, toluol and xylol. Moreover,

the efficiency of removal of said hydrocarbon oils, using a recirculated solvent, is open to improvement.

Mixtures of gasoline and aromatic light oils have been found to be advantageous motor fuels, especially by reason of the fact that the incorporation of such materials in gasoline produces the desirable effect of suppressing detonation, when used as fuel in internal combustion motors. For this reason, aromatic light oils have been admixed with gasoline and the mixture placed on the market as "anti-knock" motor fuel, thus affording an advantageous outlet for the sale of such oils recovered by gas manufacturers.

With respect to the manufacture of gasoline, it is now common practice to crack petroleum derivatives, such as gas oil, in the field, using pressure distillation processes, some of which produce as much as 40% of gasoline from gas oil. There are, however, certain disadvantages of cracking gas oil in the field. The permanent gases produced in the cracking operation are useful only as fuel in the plant, and generally no market for 70 their advantageous sale exists. Furthermore, the residuum from the cracking stills is of practically no value in an oil refinery.

My invention provides for treating fuel gas with gas oil or similar petroleum derivative, 80 without recirculation, to remove light aromatic oils from the gas, and subsequently cracking the thereby enriched gas oil to produce an advantageous motor fuel of the anti-knock character.

According to my invention, I subject fuel gas to contact with gas oil in suitable contact apparatus, for the removal of benzol and its homologues. By reason of the fact that the gas oil is not recirculated, and comes into contact with the gas substantially free from aromatic hydrocarbon oils, the efficiency of removal of the latter is increased, as compared to the usual light oil recovery process involving recirculation of solvent. When operating with fresh solvent and without recirculation, the enriched petroleum solvent removed from contact with the gas may contain as much as 8% of benzol hydrocarbons.

I then subject the enriched gas oil to a crack-

ing operation. For this operation, any suitable pressure distillation or other cracking process may be employed, for example, the "Fleming" process, the "Dubbs" process, or the like. In this stage, the oil or vapors thereof are subjected to extremely high temperatures under pressure in such manner as to convert a maximum portion of the oil into lighter products, such as gasoline. The distillate from this cracking operation, in addition to gasoline, will contain the light oils removed from the fuel gas or cracked products thereof.

In order to remove gum-forming or other objectionable constituents introduced with the aromatic hydrocarbon removed from the gas, I subject this distillate to the usual washing operations, such as treatment with sulfuric acid, caustic soda solution, "doctor solution", or the like, especially when losses caused by thorough washing of the petroleum distillates are not excessive.

The cracking process may be carried so far that a residuum of coke is obtained. The residuum may be added to the coal being carbonized, or, if coke, to the coke produced in the gas plant. In this manner, the full value of the residuum as fuel may be realized.

The permanent gases produced in the cracking operation are conducted into the gas mains, and thus realize their full value. It will be seen that, with an enrichment equal to about 8% of the petroleum solvent, if the latter is subjected to a cracking operation capable of producing 50% of the desired distillate, such distillate will contain about 16% of benzol hydrocarbons, which is a sufficient proportion to produce an anti-knock effect.

In order to prevent the breaking down of the aromatic oils, such as benzol, into diphenyl or other objectionable or undesirable compounds, I may subject the enriched gas oil, prior to the cracking operation, to steam distillation for the removal of such light oils as will interfere with, or will be undesirably affected by, the cracking operation. This steam distillation may be accomplished in the usual bell-and-tray column, or any other suitable apparatus. The gas oil passes downward through the column, in counter-current with steam and vapor, and is stripped of substantially all aromatic hydrocarbons. The latter are condensed, separated from aqueous condensate, washed to remove gum-forming constituents, and added to the distillate from the cracking operation.

The hot gas oil leaving the still is run into the pressure stills and is there cracked in the usual manner, thus effecting a saving in heat units. The light distillates from the cracking operation are added to the washed condensate from the steam distillation. This procedure is particularly advantageous when the petroleum distillate is of such character that large losses would result from thorough washing.

It will be seen that the washing necessary to remove gum-forming constituents introduced with the aromatic hydrocarbons is accomplished out of the presence of the petroleum distillates. The latter may not be washed at all, or, at most, only a light washing may be given them.

According to my invention, fuel gas may be treated by a simple process for the removal of light oils, and the recovery of such light oils is so accomplished that a desirable and readily marketable product is obtained at high efficiency. The invention further provides an advantageous process of cracking enriched petroleum distillate into motor fuel of anti-knock character, with numerous advantages and results as hereinabove set forth.

An alternate or supplementary source of benzol and its homologues available in gas plants, and within the scope of my invention, is the tar produced in the gasification of carbonaceous materials, as in coal gas or water gas manufacture, or the like. Derivatives of such tars may be added to gas oil prior to cracking the same for the purpose of making an anti-knock motor fuel, whether or not the gas oil contains similar materials derived from washing the gas directly.

My process is not limited to the use of a particular petroleum oil as solvent, though gas oil is preferred, nor to any particular means of effecting the various steps, and is to be construed as within the scope of the following claims.

I claim as my invention:

1. The process of obtaining a motor fuel which comprises treating fuel gas containing aromatic hydrocarbons with a fresh petroleum oil to remove aromatic hydrocarbons therefrom, subjecting the thereby enriched petroleum oil to steam distillation to remove the lighter aromatic hydrocarbons therefrom, subjecting the stripped petroleum oil containing the heavier aromatic hydrocarbons to a cracking operation and mixing the distillate oils from said steam distillation and said cracking operation.

2. The process of obtaining a motor fuel which comprises treating fuel gas containing aromatic hydrocarbons with a fresh petroleum oil to remove aromatic hydrocarbons therefrom, subjecting the thereby enriched petroleum oil to steam distillation to remove the lighter aromatic hydrocarbons therefrom, subjecting the stripped petroleum oil containing the heavier aromatic hydrocarbons to a cracking operation, washing the distillate oil from said steam distillation to remove gum-forming and other objectionable constituents therefrom and mixing said washed distillate oil with the distillate from said cracking operation.

3. The process of obtaining motor fuel having anti-knock properties which comprises washing coal gas containing benzene

and other benzenoid hydrocarbons with a petroleum distillate oil for the removal from said gas of said benzenoid hydrocarbons, removing the petroleum distillate oil thereby enriched with said benzenoid hydrocarbons,
5 subjecting said enriched oil to a distillation operation in which constituents of said oil are cracked to products of lower boiling point, and condensing the vapors thereby evolved to produce a liquid comprising a mixture of
10 light aromatic and aliphatic hydrocarbon oils.

In testimony whereof, I have hereunto subscribed my name.

CHARLES J. RAMSBURG.
